UNITED STATES PATENT OFFICE

140,252

DESIGN FOR A MAGNIFYING GLASS

Edward J. Herbert, Scarsdale, N. Y.

Application November 9, 1944, Serial No. 116,239

Term of patent 7 years

(Cl. D57—1)

To all whom it may concern:

Be it known that I, Edward J. Herbert, a citizen of the United States, residing in Scarsdale, Westchester County, State of New York, have invented a new, original, and ornamental Design for a Magnifying Glass, of which the following is a specification, reference being had to the accompanying drawing, forming a part thereof, in which:

Fig. 1 is a perspective view of a magnifying glass embodying my new design, the view showing the magnifying glass in open position; and

Fig. 2 is a top plan view of the magnifying glass shown in Fig. 1, the view showing the magnifying glass in closed position.

The surface of the side of the housing for the magnifying glass opposite to that shown in Fig. 2 has substantially the same appearance as that shown in Fig. 2.

I claim:

The ornamental design for a magnifying glass, as shown and described.

EDWARD J. HERBERT.
